Inventor:

Annette F. Howland
by her attorney
Charles S. Gooding,

UNITED STATES PATENT OFFICE.

ANNETTE F. HOWLAND, OF NEWTON, MASSACHUSETTS.

DESIGN FOR A TRAY.

52,657.

Specification for Design.

Patented Nov. 12, 1918.

Application filed July 2, 1918. Serial No. 243,077. Term of patent 7 years.

To all whom it may concern:

Be it known that I, ANNETTE F. HOWLAND, a citizen of the United States, residing at Newton, in the county of Middlesex and State of Massachusetts, have invented a certain new, original, and ornamental Design for a Tray, of which the following is a specification, reference being had to the accompanying drawing, forming part thereof.

In the drawings:

Figure 1 is a plan view of a tray showing my new design.

Fig. 2 is a section taken on line 2—2 of Fig. 1.

I claim:

The ornamental design for a tray as shown.

In testimony whereof I have hereunto set my hand in presence of two subscribing witnesses.

ANNETTE F. HOWLAND.

Witnesses:

CHARLES S. GOODING,
SYDNEY E. TAFT.
